FIG. 14.

Figures 1, 2, 3, 4, 5, and 6 are side elevational views, respectively, of the king, queen, bishop, castle, pawn, and knight, in a set of chessmen, showing my new design. The upper portion of Figure 4 is shown partly in section so that the slight recess around the base of the crown may appear.

Figure 7 is a side elevational view of the knight of Figure 6 in the direction of the arrow 7.

Figure 8 is a side elevational view of the knight of Figure 6 in the direction of the arrow 8.

Figure 9 is a top plan view of the knight of Figure 6. Figure 10 is a top plan view of the king of Figure 1. Figure 11 is a top plan view of the queen of Figure 2.

Figure 12 is a top plan view of the bishop of Figure 3. Figure 13 is a top plan view of the castle of Figure 4. Figure 14 is a top plan view of the pawn of Figure 5. I claim:

The ornamental design for a set of chessmen or similar article, substantially as shown.
